[57] **CLAIM**

The ornamental design for a bottle, as shown and described.

DESCRIPTION

FIG. 1 is a perspective view of a bottle showing my new design;

FIG. 2 is a front elevational view thereof, the back being essentially a mirror image of the front;

FIG. 3 is a left side elevational view thereof, the right side being essentially a mirror image of the left side;

FIG. 4 is a top plan view thereof; and

FIG. 5 is a bottom plan view thereof.

*Fig. 1**Fig. 2**Fig. 3**Fig. 4**Fig. 5*
